TELEPHONE-EXCHANGE SYSTEM.

1,355,634.

Specification of Letters Patent. Patented Oct. 12, 1920.

Application filed December 27, 1918. Serial No. 268,463.

To all whom it may concern:

Be it known that we, SAMUEL B. WILLIAMS, Jr., and BERT G. DUNHAM, citizens of the United States, residing at Brooklyn, 5 in the county of Kings and State of New York, and at Hawthorne, in the county of Passaic, State of New Jersey, respectively, have invented certain new and useful Improvements in Telephone-Exchange Systems, 10 of which the following is a full, clear, concise, and exact description.

This invention relates to an improvement in telephone exchange systems and has particular reference to a semi-mechanical private branch exchange system employing rotary line and selector switches.

The present invention is designed as a means for establishing various connections through a trunking arrangement shown in 20 an application to S. B. Williams, Jr., filed on December 27, 1918, and bearing Serial No. 268,501, and wherein groups of trunks in a selector switch are provided, certain of which have their terminals interspersed in 25 the terminal bank, while other terminals in the bank are allotted for group selection.

An object of the invention is to provide a selector switch in which means are employed, whereby an idle trunk in any group 30 individual to one of said means may be selected, without the possibility of seizing an idle trunk in any other group over which the brushes of the switch may move.

Another object is the provision of a final 35 selector or connector switch, wherein selection of certain groups of final trunks and trunks in said groups is made in accordance with impulses transmitted to said switch, and wherein the selection of another group of trunks occurs between the sending of different sets of impulses.

The inventive idea involved is capable of receiving a variety of expressions, one of which, for the purpose of illustrating the 45 invention, is shown in the accompanying drawings, but it is to be expressly understood that said drawings are employed merely for the purpose of illustrating the invention as a whole and not to define the 50 limits thereof, reference being had to the appended claims for this purpose.

In the drawings Figures 1 and 2 combined, with Fig. 2 at the right of Fig. 1,

illustrate diagrammatically the various circuits of the private branch exchange system; Fig. 3 is a diagrammatic view of the trunking arrangement employed in connection with the invention.

In carrying out the invention, switches of the rotary type having contacts arranged in a complete circle are preferably employed for interconnecting the telephone lines. In Fig. 3 wherein the trunking arrangement is disclosed, a subscriber's substation A is shown in association with a line switch B, the brushes of which are caused to move over the terminal bank by the removal of the receiver at substation A and automatically select an idle trunk, whereby the line is extended to a first selector switch C. The 60 multiple bank of this switch consists of a plurality of terminals, certain of which are available for trunks divided into groups. Two of these groups c' and c^2 are available for automatically extending a connection to selector switches D when interconnecting calling and called subscribers within the private branch exchange. The terminals of 65 said groups in the multiple bank of switch C are shown as arranged alternately, but it is to be understood that said terminals may be promiscuously interspersed or disposed at random without departing from the spirit and scope of the invention. The multiple of 70 the several banks is such that a different trunk appears as the first trunk in each multiple bank or group of multiple banks. By 75 this arrangement, the selectors will not be required to hunt over all the busy trunks and the number of busy trunks passed over will be on the average, the same when calling 80 through the first group as when calling through the second group. The other two groups of trunks c^3 and c^4 may be used in establishing connections to a private branch 85 exchange operator's position and to a central office exchange, respectively, and the terminals in the trunks of each of these groups, in contradistinction to the terminals 90 of groups of trunks c' and c^2 , are preferably arranged in the ordinary manner.

In the final selector switch D, three groups of lines d' , d^2 and d^3 are shown, and depending upon the number of tens impulses transmitted by the sender at substation A in making an automatic connection 105

to a called substation, the brushes of the final selector are stepped around to one of three terminals. The units digits of numbers in the first two groups are selected by 5 the dial impulses, but when a number in the last group is called, a group relay operates on the completion of the impulses for the tens digit, as will appear later, causing the stepping magnet of the final selector to automatically step the brushes around to the 10 last group, and the dialing of the units digit of the number then selects the desired trunk in this group.

The operation may be briefly stated as 15 follows: Should a subscriber at substation A desire a connection to the central office exchange, the removal of his receiver will first operate line switch B to seize an idle trunk. The impulse sender is then manipulated to 20 transmit one impulse which will step the brushes of the first selector switch C to the second terminal of the multiple bank, and thus select the group of central office trunks c^4 . By this selection the terminals of all the 25 other groups of trunks are rendered non-selectable, and the brushes of the switch will be stepped over these terminals and caused to hunt for an idle trunk in the group c^4 , whereupon the connection will be extended 30 to the central office.

If it is desired to automatically establish a connection between two subscribers within the private branch exchange, the calling subscriber will, by removing his receiver, seize 35 an idle trunk connected to the line switch, and by manipulating the sender to transmit two or three impulses, depending upon which of the groups c' or c^2 is to be selected, the brushes of the selector C will be stepped 40 to the corresponding terminal in the selector bank allotted to the particular group, whereupon a trunk hunting operation will proceed over the terminals of the group of trunks selected.

45 As previously stated in connection with the trunk hunting in group c^4 , the terminals of all the other groups, with the exception of the one in which trunk hunting is now proceeding, will likewise be made non-selectable, so that should all the trunks in the 50 selected group be busy, the brushes of the selector will travel over the groups of trunks c^3 and c^4 in order that a busy tone will be transmitted to a subscriber at substation A. 55 Upon the seizing of a trunk in either of the two groups c' or c^2 , the line is extended to the final selector switch which is operated, as briefly referred to above, to connect the calling and called subscribers.

60 To call the private branch exchange operator, the digit 0 is dialed to send ten impulses after a connection has been extended from the line switch, and the brushes of the selector are stepped to the terminal of the 65 bank in association with the group of trunks

c^3 , at which time a trunk hunting operation would again take place to select an idle trunk leading to the operator's position. Again, as described in connection with the trunk hunting operations in other groups, 70 the terminals thereof, in this instance, will be rendered non-selectable in order that trunks therein will not be seized.

It is believed that the invention will now be best understood from a detailed description of the operation in establishing a connection from a calling subscriber to a called subscriber, and also to central office and private branch exchange trunks. Upon the removal of the receiver at substation A, in 80 initiating a call, line relay 200 of the line switch B is energized over a circuit from grounded battery, winding of relay 200, back contact and innermost lower armature of cutoff relay 201, substation apparatus, 85 upper armature and back contact of relay 201 to ground. The marginal stepping magnet 202 is then energized over the circuit from grounded battery, winding of said magnet, armature and back contact thereof, 90 front contact and armature of line relay 200 and lowermost brush 203 to ground at the normal terminal thereof, whereupon the brushes of the switch will be stepped to the second set of terminals, the trunks of which 95 lead to one of the first selector switches. Should the selector switch connected to the first test terminal be busy, brush 203 of the line switch B engaging said terminal will be grounded at the back contact of the line relay of the line switch connected to said selector switch, and a circuit will be found for stepping magnet 202 extending from grounded battery, winding of said magnet, 100 armature and back contact thereof, front contact and armature of relay 200, brush 203, armature and back contact of the line relay of said other line switch to ground. Magnet 202 being self-interrupting, will again step 105 the brushes of the line switch over the terminal bank until an idle trunk is found, whereupon a circuit is established from grounded battery, winding of magnet 202, back contact and armature thereof, winding of relay 201 in series with said magnet, brush 204, 110 conductor 304, winding of low resistance relay 307, brush 308 of the selector switch, back contact and innermost right armature of test relay 303, and right armature of relay 301 to ground. Magnet 202, being 115 marginal and in series with relay 201, will not operate, but relays 201 and 307 will operate and the former relay will extend the subscriber's line to the idle selector switch C.

Line relay 200 deenergizes and its back contact grounds the test terminal and makes the trunk test busy to all other line switches. Line relay 309 of the selector switch will 120 energize immediately upon energization of relay 307 due to the circuit extending from 125

grounded battery, right winding of relay 309, armature and front contact of relay 307 to ground. A circuit for relay 309 will be maintained from grounded battery, right 5 winding of relay 309, back contact and innermost lower armature of cutoff relay 310, lower side of the subscriber's line, substation apparatus, upper side of subscriber's line, back contact and upper armature of relay 10 310, left winding of relay 309, brush 311 and coil 312 to ground. First slow-to-release relay 305 is then energized by a circuit extending from grounded battery, winding of relay 305 and front contact and armature of line relay 309 to ground. Operation of relay 15 305 establishes a holding circuit for relay 201 extending from grounded battery, winding of magnet 202, armature and contact thereof, winding of relay 201, brush 204, conductor 304, and left armature of relay 305 to ground. A dial tone is furnished by coil 312 to inform the subscriber that he may now operate his sending device. If the subscriber desires to establish a connection to 20 another P. B. X. subscriber, he will now transmit two or three impulses, depending upon which group of trunks c' or c^2 is to be selected for the trunk hunting operation. Interruption of the circuit of line relay 309 25 by the sending device, causes the armature thereof to vibrate, and upon each retraction a circuit is closed for the stepping magnet 313, extending from grounded battery, winding of magnet 313, winding of slow-to-release relay 301, right armature of slow-to-release relay 305 which remains energized during the line interruptions, back contact and outermost lower armature of cutoff relay 310 and back contact of the armature of 30 relay 309 to ground. The brushes of the selector are stepped from their normal terminals in accordance with the number of impulses sent, and upon deenergization of relay 301 at the termination of the transmission 35 of impulses, one of the two group relays 314 and 315 is energized. Assuming that two impulses were sent to select the group of trunks c' , group relay 314 will be energized over a circuit extending from grounded battery, winding of relay 314, brush 308 which now rests upon the third terminal in its row, back contact and innermost right-hand armature of test relay 303, and right armature of relay 301 to ground. 40 Relay 314 in attracting its right armature, energizes test relay 303 over a circuit extending from grounded battery, right winding of said relay, lowermost brush 316, the third terminal in the row associated with 45 said brush, front contact and right armature of relay 314 to ground. After test relay 303 is energized, relay 314 is held up, until an idle trunk is found, over a circuit extending from grounded battery, winding of relay 314, left armature and front contact thereof 50 and left armature of slow-to-release relay 305 to ground. Stepping magnet 313 is now operated over a circuit extending from grounded battery, winding of said magnet, armature and back contact thereof, front 55 contact and outer left armature of relay 303, front contact and right armature of relay 314 to ground. It is to be noted that the continued energization of relay 314 has removed the ground at its right armature from the terminals of the selected group c' traversed by the brush 316, but that as long as the test brush 317 of the selector is moving over busy trunks, test relay 303 is held up over a circuit from grounded battery, left 60 winding of relay 303, front contact and inner left armature thereof, test brush 317 to ground at the busy final selector. It is therefore apparent that relay 303 will not release until brushes 316 and 317 engage 65 two terminals simultaneously free from ground and consequently stepping magnet 313 continues to operate until an idle trunk is found. During the energization of test relay 303, a ground is placed upon the conductor 302, except when relay 301 is energized, and this ground provides an additional guarding potential which will prevent seizure of the selector by another line switch when the latter is hunting for an idle trunk. 70 When brushes 316 and 317 simultaneously engage two terminals free from ground, test relay 303 will retract its armatures and break the circuit for stepping magnet 313, and brushes of the selector will come to rest 75 upon the selected terminals. Cutoff relay 310 is immediately energized by the circuit extending from grounded battery, winding of relay 310, back contact and outer right armature of test relay 303, brush 308, back 80 contact and inner right armature of test relay 303 and back contact and armature of relay 301 to ground, and the line is thus extended to the final selector switch D. Upon the operation of cutoff relay 310, line relay 85 309 and slow-to-release relay 305 release, but the upper and inner lower armatures of relay 310 being of the make-before-break type, the connection is cut through and ground is found at the final selector for relay 201 and 90 group relay 314, before the ground at relay 305 is removed, and said relays thus remain energized. 95

If all of the trunks in the group are found to be busy, test relay 303 remains energized 100 until the brushes of the switch have been stepped onto the last set of terminals, at which time brush 317, no longer finding ground, will cause relay 303 to deenergize, and upon the release of relay 303, cutoff 105 relay 310 is energized over a circuit extending from grounded battery, winding of relay 310, back contact and outer right armature of relay 303, brush 317, inner left-hand armature and back contact of relay 303, 110

115

120

125

130

normal contact and left-hand armature of relay 301, left-hand armature and alternate contact of relay 305 to ground. Upon energization of cutoff relay 310, a busy tone is furnished on the calling line by a circuit extending from grounded battery, right winding of line relay 309, brush 318, lower side of the telephone line, substation apparatus A, upper side of the telephone line, brush 319 and coil 325 to ground. Through this circuit relay 309 is held energized until the receiver at substation A is replaced upon its hook. Line relay 309 then releases whereupon the slow-to-release relay 305 will become deenergized. This latter relay opens a circuit for the relay 310 at its left-hand front contact above described. The release of relay 310 closes a circuit from ground, the armature and back contact of relay 309, the lower armature and back contact of relay 310, right-hand armature and back contact of relay 305, brush 316, and right-hand winding of relay 303 to grounded battery. The energization of relay 303 closes a circuit for stepping magnet 313 from grounded battery, the winding, armature and back contact of said magnet, left-hand outer front contact and armature of relay 303, left-hand back contact and armature of relay 305 to ground, whereupon stepping magnet 313 will become energized and step the switch to normal position at which position relay 303 will be deenergized and the circuit is then restored to its normal condition. The line switch is restored to normal in a manner to appear later.

Assuming now that an idle trunk was found, upon the energization of cutoff relay 310, line relay 400 of the final selector switch D becomes energized over the circuit extended from grounded battery, right winding of relay 400, lower side of the telephone line, substation apparatus A, upper side of the telephone line and left winding of relay 400 to ground. In attracting its armature, relay 400 closes the circuit for slow-to-release relay 401 which extends from grounded battery, winding of relay 401, front contact and armature of relay 400 to ground. Relay 401 attracts its left armature and establishes the ground previously referred to in connection with the holding circuit for relay 201 and group relay 314. When relay 401 is energized, relay 402 also operates over a circuit extending from grounded battery, winding of relay 402, brush 403 in its normal position, conductor 404 to ground at the left armature of relay 401. If the desired number is within the groups of lines d' or d² of the final selector switch D, shown in Fig. 3, the impulse sending device at substation A is operated to transmit either one or nine impulses, depending in which group the line selecting operation is to take place. Assuming that the called number is

in group d', the sending device is operated to transmit one impulse, and in response thereto the armature of relay 400 will be retracted and close a circuit for the stepping magnet 405 extending from grounded battery, winding of magnet 405, front contact and inner left armature of relay 402, winding of slow-to-release relay 406, back contact and left armature of relay 407, right armature of slow-to-release relay 401 and back contact and armature of relay 400 to ground. The brushes of the switch are thereby stepped onto the second set of terminals. Upon energization of relay 406, in response to the impulse transmitted, a circuit was closed for relay 408 extending from grounded battery, winding of said relay and right armature of relay 406 to ground, and said relay 408 locked up through its outermost lower armature and front contact. 80 armature and back contact of relay 409 and left armature of slow-to-release relay 401 to ground. The group of trunks d' has now been selected and at the termination of the impulse, slow-to-release relay 406 deenergizes, but relay 402 remains energized over a circuit extending from grounded battery, winding of relay 402, brush 403, conductor 404 and left armature of slow-to-release relay 401 to ground. Upon transmitting the units impulses to select the desired line in the group d', stepping magnet 405 is again operated over the previously described circuit to step the brushes of the switch. It is to be noted that as soon as 100 the brush 403 leaves the second terminal, ground will no longer be found for relay 402 at the left armature of slow-to-release relay 401, but relay 402 will remain energized over a circuit extending from grounded battery, winding of said relay, left armature and back contact of group relay 410 and left armature of slow-to-release relay 406 to ground. Relay 406 remains energized during the transmission of impulses. 110 Stepping magnet 405 will thus continue to operate in accordance with the impulses transmitted until the brushes have been stepped upon the desired set of terminals. If the line selected is found to be busy, relay 115 402 will continue to find ground at the left armature of slow-to-release relay 406 until the same becomes deenergized at the termination of the impulses, whereupon the circuit for relay 402 will be extended from the 120 back contact of the left armature of relay 406, through relay 407, inner right armature and back contact thereof, front contact and outer left armature of relay 402, brush 411 to ground at the busy terminal of the called 125 line. Relay 407 will lock up through its inner right armature to ground at the left armature of relay 401. Attraction of the outer right armature of relay 407 furnishes a busy tone to the calling line extending 130

from grounded battery, right winding of line relay 400, lower side of the subscriber's line, substation apparatus A, upper side of subscriber's line, outer right armature of relay 407 and coil BZ to ground.

Should the called line be idle, relay 402 releases at the end of the impulses, since upon deenergization of relay 406 the ground at the left armature of the latter relay will be removed. Upon the release of relay 402, relay 412 becomes energized over a circuit extending from grounded battery, winding of relay 412, right armature and back contact of relay 402, back contact and innermost right armature of group relay 410, brush 413 and back contact and right armature of slow-to-release relay 406 to ground. Energization of relay 412 extends the line to the selected terminals and closes a circuit for relay 409 extending from the ringing current generator 414, right winding of relay 409, front contact and inner lower armature of relay 408, lower armature and front contact of relay 412, ringer apparatus at the called substation E, front contact and upper armature of relay 412 and inner upper armature of relay 408 to ground. Ringing current is thus applied to the line and is also induced into the secondary winding of relay 409 for the purpose of furnishing ringing tone to the calling station, the circuit for this ringing tone extending from grounded battery, left winding of relay 415, lower side of the telephone line, substation apparatus A, upper side of the telephone line, right winding of relay 415 and left winding of relay 409 to ground. Relay 409 is marginal and will not attract its armature as long as the resistance of the substation bell is in its circuit, but when the receiver at the called substation E is removed, said relay will become energized and break the circuit for relay 408 which extended through the armature and back contact of said relay 409. Relay 408, in releasing, disconnects the ringing current and closes the talking circuit at the innermost upper and lower armatures and back contacts, and conversation may proceed.

If the called line had been located in group d^2 , it would have been necessary to transmit nine impulses to the final selector to step the brushes thereof onto the tenth terminal shown in the bank of the selector D in Fig. 3, and in so stepping the brushes the operation would be precisely the same as that set forth above. It should be noted that no line numbered 91 appears, since the terminal which should have been allotted for line 91 is, instead, allotted for the selection of group d^3 .

Should the line be in group d^3 , the brushes are stepped around as previously described until they engage the eleventh terminal shown in Fig. 3, whereupon as soon as relay 406 releases at the end of the impulses, group relay 410 is energized by a circuit extending from grounded battery, winding of relay 410, conductor 416, brush 413, back contact and armature of relay 406 to ground. The operation of relay 410 energizes relay 402 over the circuit extending from grounded battery, winding of relay 402, left armature and front contact of relay 410 to ground. Energization of relay 410 also closes a circuit for stepping magnet 405 extending from grounded battery, winding of magnet 405, armature and back contact thereof, outermost right armature and front contact of relay 410, conductor 416, brush 413, back contact and armature of relay 406 to ground. Magnet 405 is now self-interrupting and operates to automatically step the brushes of the switch. Upon the first step of said brushes, relay 410 locks up over the circuit extending from grounded battery, winding of relay 410, front contact and innermost right armature thereof, conductor 417, brush 413, back contact and armature of relay 406 to ground. The stepping operation of the brushes continues until brush 413 reaches the terminal having no connection to the conductor 417, whereupon said brushes come to rest on this set of terminals. Relay 410 releases, but relay 402 continues to be energized over a circuit from grounded battery, winding of relay 402, brush 403, conductor 404 and left armature of slow-to-release relay 401 to ground. In response to the units impulses, the brushes are again stepped around in the line selecting movement in group d^3 , in the same manner as previously described for calling a number in group d^2 .

Should the subscriber after initiating a call, hang up his receiver before an idle trunk leading to the selector switch has been seized, it will be apparent that the line switch will continue to hunt for the idle trunk, and upon finding the same, cutoff relay 201 will be energized as previously described. Relay 307, being in series with relay 201, also energizes, and at its front contact, closes a circuit for line relay 309, which in attracting its armature, energizes slow-to-release relay 305, thus grounding conductor 304, leading from cutoff relay 201, at the left armature of relay 305, instead of at the back contact and right armature of relay 301 and thereby shunting relay 307. Release of this relay deenergizes line relay 309, since the line circuit has been broken by replacing the receiver, and armature of relay 309 closes the circuit of stepping magnet 313 extending over the previously traced circuit, and the brushes are stepped onto the second set of terminals. In response to the continued deenergization of relay 309, relay 305 releases, and after an interval relay 301 follows. Group relay 320 is then energized over a circuit extending from

6

grounded battery, winding of relay 320, brush 308, back contact and inner right armature of test relay 303, back contact and right armature of slow-to-release relay 301 to ground. The right armature of group relay 320 puts ground on the set of test terminals associated therewith, and test relay 303 is consequently energized by the circuit extending from grounded battery, 5 right winding of relay 303, brush 316, front contact and right armature of relay 320 to ground. Energization of relay 303 closes the circuit for stepping magnet 313 from grounded battery, winding of magnet 313, 10 armature and back contact thereof, front contact and outer left armature of relay 303, back contact and left armature of slow-to-release relay 305 to ground, the latter relay having become deenergized upon the release 15 of line relay 309. The brushes are now stepped to the next set of terminals, and this action takes place each time the brush 316 engages one of the terminals which finds ground at the right armature of group relay 320. When engaging the test terminals of the different groups c' , c^2 and c^3 , brush 316 finds ground for test relay 303 at the back contacts and armatures of the respective 20 group relays. When relay 320 is energized, ground for the group of terminals c^4 extends from the armature and back contact of relay 309, outer lower armature and back contact of relay 310, right armature and back contact of relay 305, outermost 25 and middle left armatures and front contacts of relay 320 to said terminals. Stepping magnet 313 continues to operate until the last set of terminals is reached, whereupon the switch is stepped to normal 30 as previously described. It is to be understood that the terminals indicated by dotted lines over which brush 316 moves, are connected to the other terminals of the respective groups in the same manner as 35 shown in full lines. Upon the shunting of relay 307, relays 309 and 305 will release and the holding circuit for relay 201 will be broken at the left armature of relay 305. Stepping magnet 202 will then operate to 40 step the switch B to normal over the circuit extending from grounded battery, winding of magnet 202, armature and back contact thereof, lowermost armature and back contact of relay 201 and brush 205 to ground 45 at the armature and back contact of line relay 200.

At the termination of a conversation, in the event that a connection has been established between the calling and called substations, the hanging up of the receiver at 50 substation A releases line relay 400 of the final selector switch D, which also causes slow-to-release relay 401 to deenergize. Relay 410 now energizes over the circuit extending from grounded battery, winding of 55

relay 410, brush 418, back contact and right armature of slow-to-release relay 401, back contact and armature of relay 400 to ground. Energization of relay 410 breaks, at its innermost right armature and back contact, the circuit for relay 412, causing this relay to release. Stepping magnet 405 is now operated over the circuit extending from grounded battery, winding of magnet 405, armature and back contact thereof, outermost right armature and front contact of relay 410, brush 418, back contact and right armature of slow-to-release relay 401, back contact and armature of relay 400 to ground, and stepping magnet 405 continues to operate until the switch is stepped to its normal position where the circuits for said relay 410 are broken.

In order to prevent the selector switch D from being seized during the return of the switch to its normal position, it being understood that the busy ground has been removed by the deenergization of slow-to-release relay 401, a ground is provided at the middle right armature and front contact of relay 410.

The removal of ground at relay 401 releases group relay 314 of selector switch C, and places ground on all trunks of the selected group associated with said relay, and thereby energizes test relay 303 over a circuit extending from grounded battery, right winding of relay 303, brush 316, terminal of the selected trunk, back contact and right armature of relay 314 to ground. Test relay 303, pulling up, opens at its right armature and back contact, the circuit for cutoff relay 310 and closes the circuit for stepping magnet 313 extending from grounded battery, winding of magnet 313, armature and back contact thereof, front contact and outer left armature of relay 303, back contact and left armature of relay 305 to ground, and stepping magnet 313 continues to operate as long as brush 316 engages a terminal which finds ground at the right armature of relay 314, and will also operate upon each engagement of brush 316 with the test terminals associated with group relays 315, 320 and 321 which are deenergized. If the brushes have selected an idle trunk in groups c' and c^2 before reaching the terminal to which they would be stepped when selecting group of trunks c^3 , relay 303, in passing over said terminal, will be energized by the circuit extending from grounded battery, right winding of relay 303, brush 316, conductor 322, back contact and left armature of relay 305 to ground, and stepping magnet 313 will thus again step the brushes onto the next set of terminals.

Line switch B is also returned to normal by the removal of ground at left armature of slow-to-release relay 401 which causes the release of cutoff relay 201, this relay

having been held energized by the circuit extending from grounded battery, winding of stepping magnet 202, armature and back contact thereof, winding of relay 201, brush 5 204, conductor 304, left armature and back contact of relay 301, back contact and inner left armature of relay 303, brush 317 and left armature of relay 401 to ground. The release of relay 201 energizes stepping magnet 202 over a circuit extending from grounded battery, winding of magnet 202, armature and back contact thereof, lowermost armature and back contact of relay 201 10 and brush 205 to ground at the armature and back contact of line relay 200. Stepping magnet 202 continues to operate until the brushes thereof engage the normal terminals, whereupon the operating circuit of said magnet will be broken and the switch will 15 come to rest.

If it is desired to establish a connection to a central office, subscriber at substation A, by removing his receiver, will operate line switch B to select an idle trunk leading to 20 one of the first selectors, and upon transmitting a single impulse the brushes of said selector will be stepped, as previously described, onto the second set of terminals, and thus select the group of trunks c^* for the 25 trunk hunting operation which automatically takes place in the same manner as described in connection with the extension of a call through group of trunks c' , group relay 320, in this instance, becoming energized.

Should the service of substation A be restricted, a conductor 207 is employed to connect the middle lower armature of cutoff relay 201 of the line switch with brush 40 206, so that if an attempt is made to call the central office from this station, energization of cutoff relay 201 will apply said ground to the central office trunks and cause the same to test busy, said ground extending through conductor 207, brush 206, conductor 323, front contact and middle left armature of group relay 320, which has become energized, to the terminals of the central office trunks. Stepping magnet 313 45 will therefore continue to operate until the last set of terminals is reached, whereupon test relay 303 will be energized over a circuit extending from grounded battery, right winding of relay 303, brush 316, the last 50 test terminal, outermost left armature and front contact of relay 320, conductor 323, brush 206 and middle lower armature and front contact of relay 201 to ground, thus causing the stepping magnet to again operate and return the switch to normal position. Line switch B, however, remains in its actuated position as long as the receiver 55 is off the switchhook, and the subscriber may again manipulate his dial to call the 60 private branch exchange operator.

To establish a connection to the private branch exchange operator's position, the sending device at substation A is actuated after the seizure of an idle trunk by the line switch B, to transmit ten impulses to step 70 the brushes onto the eleventh set of terminals, whereupon group of trunks c^* will be selected for the trunk hunting operation, and in this case group relay 321 will be energized to remove ground from the terminals of the private branch exchange trunks 75 over which test brush 316 passes and one of the trunks will be seized in the same manner as previously described.

What is claimed is:

1. In a telephone exchange system, a selector switch having a terminal bank, groups of trunks connected to certain terminals of said bank, other terminals thereof being allotted for group selection, and means for 80 moving the switch over the last named terminals and terminals of groups of trunks in selecting an idle trunk in a selected group.

2. In a telephone exchange system, a selector switch having a terminal bank, groups of trunks connected to certain terminals of said bank and having their terminals interspersed, other terminals of said bank being allotted for group selection, and means for 85 moving the switch over terminals allotted for group selection and also terminals of non-selected groups in selecting an idle trunk in a selected group.

3. In a telephone exchange system, a rotary selector switch having a terminal bank, groups of trunks connected to said bank and having their terminals arranged in interspersed relation, other terminals of said bank being allotted for the selection of a 90 particular group, and means for moving the switch over terminals allotted for group selection and also terminals of a non-selected group in selecting an idle trunk in 95 a selected group.

4. In a telephone exchange system, a selector switch having a terminal bank, groups of trunks connected to certain terminals of said bank, other terminals of said bank being allotted for group selection, one of said 100 other terminals being arranged between terminals of two of said groups, and means for moving the switch over said other terminals and also terminals of certain groups in selecting an idle trunk in another group. 105

5. In a telephone exchange system, a selector switch having a terminal bank, groups of trunks connected to said bank and having their terminals interspersed, other terminals of said bank being allotted for group 110 selection, and means for initially moving said switch onto one of the latter terminals to select a group and then moving the same over terminals of another group in selecting an idle trunk in the selected group. 115

6. In a telephone exchange system, a selector switch having a terminal bank, groups of trunks connected to said bank and having their terminals interspersed, other groups of trunks also connected to said bank, certain other terminals of said bank being allotted for group selection, one of the latter terminals being arranged between terminals of the first named groups, and means for moving the switch over said other terminals and terminals of said first named groups in selecting an idle trunk in one of the second named groups. 5
7. In a telephone exchange system, a selector switch having a terminal bank, groups of trunks connected to said bank and having their terminals interspersed, other groups of trunks also connected to said bank, certain other terminals of said bank being allotted for group selection, one of the latter terminals being arranged between terminals of the first named groups, and means for moving the switch over the other of said latter terminals and terminals of the first 10 named groups and onto the terminal arranged between terminals of said first named groups to select one of the second named groups for trunk hunting operation therein. 20
8. In a telephone exchange system, a selector switch having a terminal bank, groups of trunks connected to certain terminals of said bank, test terminals for said groups, a relay assigned to each group, means for energizing one of said relays to place a certain electrical condition upon the test terminals of the group of trunks associated therewith, and means for moving said switch over other test terminals of said group until a terminal is found having the same electrical condition as the first named test terminals of said group. 30
9. In a telephone exchange system, a selector switch having a terminal bank, groups of trunks connected to certain terminals of said bank, test terminals for said groups, electromagnetic means assigned to each group, means for energizing one of said electromagnetic means to place a certain electrical condition upon terminals of the group of trunks associated therewith, and means for moving said switch over other test terminals of said group until a terminal is found having the same electrical condition as the first named test terminals of said group. 40
10. In a telephone exchange system, a selector switch having a terminal bank, groups of trunks connected to certain terminals of said bank having their terminals interspersed, test terminals for said groups, electromagnetic means assigned to each group, means for energizing one of said electromagnetic means to place a certain electrical condition upon terminals of the group 50
- of trunks associated therewith, and means for moving said switch over other test terminals of said group until a terminal is found having the same electrical condition as the first named test terminals of said group. 55
11. In a telephone exchange system, a selector switch having a terminal bank, groups of trunks connected to certain terminals of said bank, other terminals being allotted for group selection, test terminals for said groups, means for selecting one of said other terminals, means operated thereupon to place a certain electrical condition upon test terminals of the selected group, and means for moving the switch over certain of said other terminals and terminals of the selected group in selecting an idle trunk therein. 70
12. In a telephone exchange system, a selector switch having a terminal bank, groups of trunks connected to certain terminals of said bank, other terminals being allotted for group selection, test terminals for said groups, means for selecting one of said other terminals, means operated thereupon to place a certain electrical condition upon test terminals of the selected group, and means for moving the switch to hunt an idle trunk in the selected group, the test for said idle trunk being predetermined by the finding of another test terminal having the same electrical condition as the test terminals of the selected group. 80
13. In a telephone exchange system, a selector switch having a terminal bank, groups of trunks connected to certain terminals of said bank, test terminals for said groups, a relay assigned to each group, means for energizing one of said relays to place a certain electrical condition upon the test terminals of the group of trunks associated therewith, and means for moving said switch over other test terminals of said group until a terminal is found having the same electrical condition as the first named test terminals of said group, the last named means being operated by the finding of a certain other electrical condition at an armature of said relay. 90
14. In a telephone exchange system, a selector switch having a terminal bank, groups of trunks connected to certain terminals of said bank and having their terminals interspersed, other terminals of said bank being allotted for group selection, test terminals for said groups, means for selecting one of said other terminals, means operated thereupon to place a certain electrical condition upon test terminals of the selected group, and means for moving the switch over certain of said other terminals and terminals of the selected group in selecting an idle trunk therein. 100
15. In a telephone exchange system, a se- 110
- 115

- lector switch having a terminal bank, groups of trunks connected to certain terminals of said bank and having their terminals interspersed, other terminals of said bank being allotted for group selection, test terminals for said groups, means for selecting one of said other terminals, means operated thereupon to place a certain electrical condition upon test terminals of the selected 5 group, and means for moving the switch to hunt an idle trunk in the selected group, the test for said idle trunk being determined by the finding of another test terminal having the same electrical condition as the test 10 terminals of the selected group.
16. In a telephone exchange system, a selector switch having a terminal bank, groups of trunks connected to certain terminals of said bank and having their terminals interspersed, test terminals for said groups, a relay assigned to each group, means for energizing one of said relays to place a certain electrical condition upon the terminals of the groups of trunks appropriated therewith, and means for moving said switch over other test terminals of said group until a terminal is found having the same electrical condition as the first named test terminals of the group, the last named means being operated by the finding of a certain other electrical condition at an armature of 20 said relay.
17. In a telephone exchange system, a selector switch having a terminal bank, groups of trunks connected to said bank and having their terminals interspersed, other terminals of said bank being allotted for group selection, a line relay, a stepping magnet responsive to interruptions at said line relay for moving the switch onto one of said other terminals to select the associated group of trunks, a relay assigned to each group, means for energizing the last named relay when the associated group is selected, and a 30 circuit for said stepping magnet closed upon energization of said last named relay for causing said stepping magnet to move the switch over terminals of the selected group to hunt an idle trunk therein.
18. In a telephone exchange system, a selector switch having a terminal bank, groups of trunks connected to said bank, other terminals of said bank being allotted for group selection, a line relay, electromagnetic 40 means responsive to interruptions at said line relay for moving the switch onto one of said other terminals to select the associated group of trunks, other electromagnetic means assigned to each group of trunks, means for energizing said other electromagnetic means when the associated group is selected, and a circuit for the first named electromagnetic means closed upon energization of said other electromagnetic means 50 for causing said first named electromagnetic 55 means to move the switch over terminals of the selected group to hunt an idle trunk therein.
19. In a telephone exchange system, a telephone line, a selector switch for extending said line and having test brushes, groups of trunks served by said switch, means for operating said switch to select a group of trunks, electromagnetic means associated with each group of trunks and energized upon the selection thereof to place a certain electrical condition upon the terminals of said group, and means for operating the switch to hunt an idle trunk in the selected group, the seizure of a trunk depending 60 upon the test brushes simultaneously engaging terminals having said certain electrical condition.
20. In a telephone exchange system, a telephone line, a rotary selector switch for extending said line and having test brushes, groups of trunks served by said switch and having their terminals interspersed, a stepping magnet operable to step said switch to select a group of trunks, a relay associated with each group of trunks and energized upon the selection thereof to place a certain electrical condition upon the terminals of the selected group with which one of said test brushes is associated, and means for continuing the operation of said stepping magnet until the other test brush engages an associated terminal having the same electrical condition as that applied to the last 70 named terminal.
21. In a telephone exchange system, a telephone line, a selector switch for extending said line, a terminal bank for said switch, groups of trunks connected to certain of the terminals of said bank, other terminals being allotted for group selection, means for stepping said switch over certain of said other terminals to select one of them, and means for continuing the operation of said stepping means whereby the 80 brushes of the switch are caused to move over terminals of non-selected groups in seeking an idle trunk in the selected group.
22. In a telephone exchange system, a telephone line, a selector switch for extending said line, a terminal bank for said switch, groups of trunks connected to certain of the terminals of said bank, other terminals being allotted for group selection, means for stepping the brushes of said switch over certain of said other terminals and also terminals of certain groups to select one of said other terminals, and means whereby the operation of said stepping means is continued over terminals of another group in hunting an idle 90 trunk in the selected group.
23. In a telephone exchange system, calling and called substation lines, switching means for extending a call from the calling substation line, a selector switch for con- 100
- 110
- 120
- 125
- 130

- necting the calling line to the called line and including a terminal bank, groups of trunks connected to certain of the terminals in said bank, other terminals being allotted 5 for group selection, and directly controlled means moved over certain of said other terminals and also terminals of certain groups in selecting an idle trunk in the selected group leading to said called 10 substation line.
24. In a telephone exchange system, calling and called substation lines, an impulse sending device at the calling substation, switching means for extending a call from 15 the calling substation line, a selector switch for connecting the calling line to the called line and including a terminal bank, groups of subscribers' lines connected to certain of the terminals in said bank, other terminals 20 being allotted for group selection, directly controlled means moved over certain of said other terminals in response to the tens impulses of the called number to select one of said groups and moved over the terminals 25 of the selected group in response to the units impulses of said called number to seize the called line, and means for automatically operating said directly controlled means during the interval between 30 the transmission of the tens and units impulses to move said means over terminals of a non-selected group.
25. In a telephone system, a trunking arrangement comprising groups of trunks, the 35 trunks of one group being promiscuously interspersed between the trunks of other groups, means to select a group, and means to select a trunk in said selected group.
26. In a telephone system, a trunking arrangement comprising groups of trunks, the trunks of one group being promiscuously interspersed between the trunks of other groups, and means to simultaneously identify 40 a group and an idle trunk in that group.
27. In a telephone exchange system, a selector switch having fixed terminals and moving contacts coöperating therewith, groups of lines connected to said terminals, 45 other terminals being allotted for group selection, lines of said groups and said group selection terminals being interspersed in order of their appearance, and means for moving said contacts over said terminals to 50 select an idle line.
28. In a telephone exchange system, a selector switch having a terminal bank, groups of subscribers' lines connected to certain terminals of said bank, other terminals being allotted 55 for group selection, directly controlled means for moving the switch over terminals of one of said groups, and means for automatically moving the switch over terminals of another group to 60 select still another group for a line selecting operation therein.
29. In a telephone exchange system, a selector switch having a terminal bank, groups of subscribers' lines connected to certain terminals of said bank, other terminals being allotted 65 for group selection, directly controlled means for moving the switch over certain of said other terminals and terminals of one of said groups, and means for automatically moving the switch over terminals 70 of another group to select still another group for a line selecting operation therein.
30. In a telephone exchange system, a selector switch having a terminal bank, groups of subscribers' lines connected to certain terminals of said bank, other terminals being allotted 75 for group selection, directly controlled means for selecting one of said other terminals, and means for automatically moving the switch over certain line 80 terminals in selecting the group of subscribers' lines associated with said other terminal.
31. In a telephone exchange system, a single movement switch, groups of subscribers' lines terminating in said switch, means for selecting a group 85 decimal and automatically, and means for then selecting a line decimal.
32. In a telephone system, a switch having a movement in a single plane, a wiper for said switch, groups of subscribers' lines terminating in said switch, said subscribers' lines being 90 decimal designated, and means responsive to trains of impulses to step said wiper to select a group of lines and a line in said group, the steps of said wiper in the group and line selecting movements being of equal length.
33. In a telephone exchange system, an impulse sending device, a switch responsive to said sending device and comprising stationary terminals, and a movable terminal arranged to move in a single plane, a plurality of groups of subscribers' lines terminating 95 in said stationary terminals, and means responsive to impulses sent by said sending device on a decimal basis for moving said movable wiper to select a group and a line in said group, the movements 100 of the wiper being of equal length.
34. In a telephone exchange system, an automatic switch, a terminal bank therefor, groups of lines connected to certain terminals on said bank, other terminals being allotted 105 for group selection and interspersed between said groups of lines, means for selecting a group of lines decimal, and means for selecting a line decimal.
35. In a telephone exchange system, a switch having a movement in one direction only, groups of connectors, groups of trunks connected to said switch and terminating in 110

said connectors, other groups of trunks, operators' positions in which said other groups terminate, and means for moving said switch to select any one of said groups by a single 5 set of impulses.

36. In a telephone exchange system, a switch having a movement in one direction only, a local position, a distant position, groups of trunks connected to said switch 10 and terminating at said positions, and means operated by a single set of impulses for moving said switch to select any one of said trunks.

37. In a telephone exchange system, a switch having a movement in one direction only, a plurality of trunks connected to said switch for extending a calling line toward a called line, a plurality of other trunks for extending a calling line to an 15 operator's position, a stepping magnet for moving said switch to select any one of said trunks, and means whereby said stepping magnet will restore said switch to normal. 20

38. In a telephone exchange system, a switch having a movement in one direction only, a plurality of trunks connected to said switch for extending a calling line toward a called line, a plurality of other trunks for extending a calling line to an operator's position, a stepping magnet operated by a single set of impulses for moving said switch to select any one of said trunks, and means whereby said stepping magnet will restore said switch to normal. 25 30

39. In a telephone system, a trunking arrangement comprising groups of trunks, the trunks of one group being promiscuously interspersed between the trunks of other groups, and means to identify a group and an idle trunk in that group. 35

In witness whereof we hereunto subscribe our names this 23rd day of December, A. D., 1918.

SAMUEL B. WILLIAMS, JR.
BERT G. DUNHAM.
